UNITED STATES PATENT OFFICE.

ARTHUR J. CURREN, OF ELYRIA, OHIO.

DESIGN FOR AN AUTOMATIC-TELEPHONE-DIAL SUPPORT.

57,213.

Specification for Design.

Patented Mar. 8, 1921.

Application filed October 20, 1919. Serial No. 332,127. Term of patent 14 years.

To all whom it may concern:

Be it known that I, ARTHUR J. CURREN, a citizen of the United States, residing at Elyria, in the county of Lorain and State of Ohio, have invented a new, original, and ornamental Design for Automatic-Telephone-Dial Supports, of which the following is a specification, reference being had to the accompanying drawings, forming a part thereof, and in which drawings:

Figure 1 is a front view;

Fig. 2 is a side view, and

Fig. 3 is a rear end view, which views show my new design.

I claim:

The ornamental design for an automatic telephone dial support as shown.

In witness whereof, I hereunto subscribe my name this 13th day of October, A. D. 1919.

ARTHUR J. CURREN.
